(57) **CLAIM**

The ornamental design for a sheet preparation to be applied on a human body, as shown and described.

DESCRIPTION

FIG. 1 is a front perspective view of a sheet preparation to be applied on a human body showing our new design; FIG. 2 is a front view thereof;

FIG. 3 is a top view thereof;

FIG. 4 is a right side view thereof;

FIG. 5 is a left side view thereof;

FIG. 6 is a rear view thereof;

FIG. 7 is a bottom view thereof; and,

FIG. 8 is an enlarged cross-section view taken along line 8-8 in FIG. 2.

The speckled shading illustrates light transmitting, e.g., semi-transparent, internal gel preparation. The dark stippled shading illustrates colored substances mixed in the gel preparation.
